UNITED STATES PATENT OFFICE.

CHARLES L. BATES, OF NEW YORK, N. Y.

GONG-BELL.

SPECIFICATION forming part of Letters Patent No. 231,752, dated August 31, 1880.

Application filed June 5, 1880. (Model.)

To all whom it may concern:

Be it known that I, CHARLES L. BATES, of the city, county, and State of New York, have invented a new and useful Improvement in 5 Gong-Bells, of which the following is a specification.

Figure 1 is a plan view of the improvement, the bell being removed. Fig. 2 is a side elevation of the same, the bell being shown in 10 section.

Similar letters of reference indicate corresponding parts.

The object of this invention is to furnish gong-bells so constructed as to give a heavier blow with a shorter stroke than those constructed in the ordinary manner, which can be adjusted for use as a right-hand or a left-hand bell, as required, and which shall be simple in construction and not liable to get out of order.

20 The invention consists in constructing a gong-bell of a frame having a stud and bell, the hammer-lever and its stop, the angle trip-lever having a toe, an incline, and a shoulder and its stops, the spiral spring, the wire lever having notch, and the two studs having screw-holes, whereby the hammer-lever is operated by the movement of the trip-lever and the action of a single spring, as will be hereinafter 25 fully described.

30 A represents the plate or frame of the bell. To the middle part of the frame A is attached the post B, that carries the bell C.

D is the hammer-lever, which is curved to bring its free end into such a position that the 35 hammer-head will strike the bell fairly. The hammer-lever D is pivoted near its rear end to the frame A by a screw, E, and its forward movement is stopped at the proper point by a stop, F, attached to the frame A.

40 G is the trip-lever, which has a projection or toe, H, upon the end of its long arm g, which engages with the end of the hammer-lever D to draw back the hammer to give a blow. Just above the toe H are formed two 45 bends at nearly a right angle, and near the pivot-screw I two bends at an obtuse angle.

The trip-lever G is pivoted at its angle at the other side of the frame A from the hammer-lever D, by a screw, I, to the lever J, 50 which is pivoted at one end to a corner of the frame A by a stud, R, and screw K, and to its

other end is attached the bell-wire L. To the end of the short arm g' of the trip-lever G is attached the end of a spiral spring, M, the other end of which is attached to the hammer-lever D. 55

With this construction, when the bell-wire is pulled the lever J is moved outward, which draws back the trip-lever G, causing the toe H to draw back the hammer to give a blow, 60 and at the same time increasing the tension of the spring M.

Upon the long arm of the trip-lever G is formed an incline, N, which rests against a stop-pin, O, attached to the frame A. As the trip-lever G is drawn back by the movement of the wire lever J, the stop O, acting upon the incline N, pushes the said trip-lever G outward and withdraws the toe H from the end of the hammer-lever D, and allows the hammer to be 70 drawn forward by the tension of the spring M to strike the bell C.

The outward and rearward movement of the trip-lever G is limited by a stop-pin, P, attached to the frame A, and against which a 75 shoulder, Q, formed upon the said trip-lever G, strikes.

The screw K screws into a screw-hole in the stud R, attached to the corner of the frame A, which stud serves as a pivot to the lever J. 80 In the inner edge of the lever J, toward the end to which the wire L is attached, and at an equal distance with the hole for the stud R from the hole for the screw I, is formed a notch, S, to receive the stud T, attached to the corner of the frame A, and which serves as a stop to prevent the said lever J, when the tension upon the wire L is relaxed, from being drawn too far inward by the spring M. The stud T has a screw-hole formed in it to receive the screw K. 85

With this construction, by taking out the 90 screws I and K, reversing the lever J, replacing the screw I, and inserting the screw K in the stud T, the bell is changed from a right-hand to a left-hand bell.

This construction makes the bell very convenient in use, as the bell-hanger can adjust the bell in a minute for attachment to the wall at either side of the doorway, as may be required. 95

I am aware that it is not new to use a sliding lever to which the wire is attached, pro-

vided with a V-shaped projection and a notched end to engage a lug on its hammer, the said lever being connected with the hammer by a spring.

5 Having thus described my invention, I claim as new and desire to secure by Letters Patent—

1. A gong-bell constructed substantially as herein shown and described, consisting of the frame A, having stud B and bell C, the angle trip-lever G, having toe H, incline N, and shoulder Q, the spring M, the wire lever J, the

studs R T, having screw-holes, and the stops F O P, as set forth.

2. In a gong-bell, the combination of the 15 wire lever J, having the notch S at the same distance from the trip-lever G as the pivot-hole in the end of said lever, with the internally-threaded studs R T, as and for the purpose specified.

CHARLES L. BATES.
